SEWER CLEANING MACHINE

Karl J. Kollmann, Erie, Pa.

Application October 21, 1958, Serial No. 53,053

Term of patent 14 years

(Cl. D9—2)

Fig. 1 is a side elevational view of a sewer cleaning machine embodying my new design with the hose shown broken away in part to indicate indeterminate length;

Fig. 2 is a reduced top plan view thereof with the cutting tool omitted for convenience of illustration; and

Fig. 3 is a front elevational view of Fig. 2; and

Fig. 4 is a fragmentary rear view of the handle end shown in Fig. 1.

The dominant features of my design reside in the portions shown in full lines.

I claim:

The ornamental design for a sewer cleaning machine, as shown and described.
